UNITED STATES PATENT OFFICE.

LEVERETT A. MANWARING, OF LEONARD BRIDGE, CONNECTICUT, AS-SIGNOR OF ONE-HALF TO WILBUR L. L. SPENCER, OF LEBANON, CONNECTICUT.

THILL-COUPING.

SPECIFICATION forming part of Letters Patent No. 773,082, dated October 25, 1904.

Application filed July 6, 1904. Serial No. 215,507. (No model.)

To all whom it may concern:

Be it known that I, LEVERETT A. MANWARING, a citizen of the United States, residing at Leonard Bridge, in the county of New London and State of Connecticut, have invented a certain new and useful Improvement in Thill-Couplings, of which the following is a specification.

The chief aim of my present invention is to provide extremely simple, cheap, and strong means for connecting the thills or pole of a vehicle to the running-gear, my said device being of such a character that the thills or pole (as the case may be) may be instantly disconnected from the running-gear without the aid of a wrench or other implement.

My said invention is illustrated in the accompanying sheet of drawings, in which—

Figures 1 and 2 are elevations of my new thill-coupling, showing opposite sides of the same and also illustrating the manner of connecting the coupling to the front axle and thills of a vehicle. Fig. 3 is a relatively enlarged view of the said coupling as viewed from the direction indicated by the arrow in Fig. 1. Figs. 4 and 5 are inner face views of the two companion parts of the coupling, and Figs. 6 and 7 are edge views of the same parts.

Referring to the drawings, the letter *a* indicates the axle of a vehicle, and the letter *b* denotes a clip of ordinary construction, by means of which one member, *c*, of the thill-coupling is clamped to the axle. The other member, *d*, of the coupling extends upward and forward, as at *d'*, and is bolted or otherwise secured to the thills *e*. The clutch member *d* is of disk form and is provided with a central projection *d''*, upon which is mounted a washer *d³*, of rawhide or the like yielding material, that is partially seated in a circular depression *d'*. The companion member *c* of the coupling is also of disk form and is provided with a central opening *c'*, adapted to receive the described projection *d''*, and also with a depression *c''*, that is adapted to receive the washer *d³* when the coupling parts are assembled for use. Disk *d* is formed with a post or extension *d⁴*, whose free end portion is

turned inward—that is to say, toward the projection *d''*—and is adapted to hook over the 50 edge of the member *c* when the parts are assembled. (See Figs. 1 and 3.) The coupling member *c* is likewise provided with a post or extension *c⁴*, whose free end is turned inward to hook over the edge of disk *d* when the coupling parts are assembled, as seen in Figs. 2 and 3.

In order to assemble the described coupling members, I have notched the edge of disk *d*, as at *d⁵*, to receive the hook *c³* and have correspondingly notched the disk *c*, as at *c⁵*, to receive the hook *d⁴* and have also cut away the edges of disks *d* and *c*, as at *d⁶* and *c⁶*, in order that the said disks may rock upon each other a limited distance without engaging the 65 posts *d⁴ c³*. The notches and hooks which I have just described are so located with respect to each other that the notch of one disk coincides with the hook of the other disk when the coupling parts are in proper position for 70 assembling, and the said notches and posts are so located with respect to the thills that the latter must be raised to a point considerably above their operative or working position in order to assemble or disengage the coupling 75 parts. This will be best understood by reference to the Figs. 1 and 2, in which the thills are shown in working position.

In order to release the thills from the running-gear, it will be obvious that the thills 80 must be raised a distance sufficient to bring the posts *d⁴ c³* into coincidence with the notches *c⁵ d⁵*, respectively, when the thills and attached coupling members *d* may be moved laterally a distance sufficient to withdraw the central 85 projection *d''* of disk *d* from the central opening *c'* of the disk *c*, when the thills may be completely removed from the vehicle proper. It will thus be seen that so long as the thills remain in their working position the coupling 90 parts cannot be separated from each other; but by simply elevating the thills a short distance the interlocking parts—to wit, the hooks *d⁴ c³* and the co-operating edges of disks *c* and *d*—may be readily disconnected.

The yielding washer *d³*, which I have re-

ferred to, should preferably be of such thickness that it will be slightly compressed when the coupling parts are assembled and interlocked, thus preventing the rattling of the parts. I preferably provide on the disk *c* a raised flange *c*⁶, which serves as a sand-band when the disks are assembled. In Fig. 4 of the drawings this sand-band is illustrated at the lower side of disk *c*; but when the said disk is reversed and mounted on the companion disk *d* the sand-band will be located at the top side of said disk *c*, as seen in Fig. 1.

My described device requires but two simply-constructed metallic parts and is of such a nature that it provides the needed strength with the minimum weight of material. It may be readily operated without the use of tools and will be found particularly convenient for use in that class of vehicles with which

both thills and a pole are interchangeably used.

Having thus described my invention, I claim—

In combination in a thill-coupling, companion disks, means for supporting said disks in concentric relation to each other, a yielding washer located between the said disks, a sand-band carried by one of said disks, and means for preventing accidental separation of the said disks.

In testimony whereof I have signed my name to this specification in the presence of two subscribing witnesses.

LEVERETT A. MANWARING.
